Philip Clinton Curtis
Letter Patent 1391X

The schedule referred to in these Letters Patent and making part of the same containing a description in the words of the said "Inventor" himself of an invention.

Water Frame. The improvements which I claim as my invention in the Loom are, the taking up of the cloth on the cloth-roller or beam as the process of weaving is performed, and the mode of communicating motion to the shuttle. The loath, or Batten and the basset by a revolving grooved cylinder turned by a ratchet or otherwise. On one end of the Cloth roller or Beam, I place two ratchet wheels one of which is permanently attached to the roller, and which I term the taking up wheel. the other, which is near the frame, moves round the beam, being prevented however from changing its position than unless operated on by the hand or pull, by a spring which pushes upon it from a fixed beam or bar below. The pull or hands which act up on these ratchet wheels are fixed near the lower end of a vertical beam, turning on pivots near the centre, they are kept down upon the wheels by weights or springs and have a cord or communication rising from one of them to the end of a balance lever above the beam, and descending from the opposite end of the said balance lever to the other pull or hand, so that when one of the hands is depressed by the spring or weight into the notch of its ratchet wheel, the pull or hand shall be raised out of the notch of its wheel, one only of the pulls or hands acting on its wheel at one time. The upper end of the beam which holds the pulls, is moved backwards and forward by a horizontal fulcrum connected also with the

vertical line which forms that side of the Lath or Ratten. The mode in which these catchet-wheels and bands or halts act is this: the catchet-wheel which moves round the beam has its periphery so divided into teeth that the full swing of the Ratten pull causes the fall or band so far back as to receive it in notch, and suffer the band to fall again, and so as to keep the other fall or band which works upon the taking-up-wheel out of the teeth thereof, by means of the coil above-mentioned, when however so much is worn on the web that the Lath or Ratten cannot have its full swing, then the fall does not enter the notch in moving catchet-wheel but will rest on its edge between the notches, and the other fall or band which acts upon the taking-up-wheel will fall into the notches thereof, and the moving backward of the Ratten will propell the catchet-wheel and roller by means of the band or fall, and as much of the web will be wound upon the roller as will allow the Ratten again to have its full swing, and the fall on the moveable catchet-wheel to have a operation.

From near the middle of the transverse bar which extends across the frame in front of the loom, the web horizontally lengthwise of the loom to another bar under the loom, a grooved cylinder which is turned by a hand or in any other manner and communicates all the motion necessary to the process of weaving. This cylinder may be of any convenient diameter, and acts in the following manner. For throwing the shuttle, there are two upright or vertical lavers having their lower extremities attached by pins to an horizontal beam at the bottom of the frame. From each of these lavers, near the top, just projects a pin which enters a groove in the cylinder which has one side cut spirally round the frame so as to turn the upper end of the lavers alternately forward towards

front of the loom, they being drawn back to their position suddenly by a weight which acts on them by a cord and pulling at each revolution of the cylinder. There is another cord wire, chain or otherwise, extending from the head of each of these levers to an upright cylinder to which they are fastened, or to arms projecting from an upright roller on the transverse bar above mentioned, so that as the levers advance towards or are by the weights drawn from, the front of the loom, they will give this cylinder or roller a motion from side to side. An arm extending from this cylinder or roller horizontally, either above or below the bar of the lathe or batten throws the shuttle in the same manner as it is now thrown in weaving with the fly shuttle. For moving the batten backwards, preparatory to the stroke, there is a frame, moved by the cylinder above described. This frame has horizontal sets of bars extending from side to side of the loom, and turning on pivots in the lower side sets thereof. From this arises at each extremity a bar which may have its upper ends connected with the batten. There are two other upright bars extending from the lower bar of this frame one on each side of the cylinder, and which have projecting pins that enter a groove therein, and are by it raised backward so as to move the lathe. The lathe is moved forwards and makes its stroke by means of weights acting on uprights extending above its hanging pins, or by springs as may be deemed best in practice. The end of the cylinder nearest the centre of the loom has upon it placed a wheel with several teeth, which acts on a similar wheel on the top of one or more vertical cylinders, which by grooves and pins move any number of treadles extending from the back part of the frame. There may be friction rollers interposed on the

the pins which act in two grooves of the cylinders of four
measuring. The other parts of the loom are of the usual
construction, and made to suit the nature of the business
to be performed, and the force employed may be either
manual or that of Horses, water, wind or Steam, as
may best suit in the manufacture where this loom is
introduced.
